2,058,364

STRUT AND ANTSHEARING MEMBER
FOR GIRDERS

Henry Sorensen, Los Angeles, Calif.

Application January 16, 1936, Serial No. 59,419

5 Claims. (Cl. 72—71)

I desire to obtain Letters Patent on a device which will greatly benefit the modification of structure shown in my U. S. Patent #1,716,710, June 11, 1929 and my U. S. Patent #1,785,214, 5 Dec. 16, 1930, or any other structure for which my invention, herein, may be adapted.

My invention, herein, consists of a simple manner to arrange strut and anti-shearing members for girders.

10 I have described my invention, and shown the same, in the following specification and its accompanying drawing, of which:—

Fig. 1 illustrates the side view of the fragment of a steel frame structure containing my invention.

15 Fig. 2 is a plan view of part of the structure shown in Fig. 1.

Fig. 3 is a fragment of the end view of Fig. 1 taken at 1—1.

20 Fig. 4 illustrates Fig. 1 embedded in concrete.

Fig. 5 is the fragment of a plan view which illustrates a further part of my invention.

Fig. 6 illustrates a modification of the structure.

25 Similar numerals designate similar parts, and numeral 1 designates the outside wall girder of a steel frame structure. 2 designates an inside girder. 3 are the top flanges of girders 1 and 2.

4 designates flat bars. 5 are spacing members. 6 is a strut member indicated by broken lines.

7 are reinforcements. 8 are looped ends of reinforcements 7. 9 is seam welding. 10 are wedges. 11 are members that assume a strut and anti-shearing action. 12 is the bottom flange of

35 girder 1. 13 is the web of girder 1. 14 is the outside edge of flange 12. 15 is the point of contact between flange 3 and web 13 on the outer side of girder 1. 16 is bracing material. 17 is concrete. 18 is a column. 19 are other members

40 that assume a strut and anti-shearing action. 20 is a strut supporting beam or other means of strut support.

To the top flanges 3 of girder 1, and girder 2, I attach flat bars 4. Bars 4 are spaced from

45 flanges 3 by means of spacers 5 and I prefer to attach members 3, 4, and 5 together by means of welding, while having members 5 suitably spaced. Spacers 5 and flat bars 4 thus become one with flange 3 and form a spaced double top flange 3 for girders 1 and 2. Bars 4 and flanges 3, preferably have the same width.

50 Reinforcements 7 have looped ends 8, as shown in Fig. 2, that are held together by means of seam welding 9. These looped ends 8 are passed through the spaces between bars 4 and flanges

3, and wedges 10 are thereupon driven into looped ends 8, which extend from between 3 and 4 to a suitable distance beyond the edges of 3 and 4, so that wedges 10 are driven against the edges of flanges 3 and bars 4, thereby locking looped ends 8 to flanges 3 while holding reinforcements 7 in initial tension. In this manner wedges 10 lock and connect reinforcements 7 in initial tension with girders 1 and 2.

It will be, further, understood that no initial tension can be maintained in reinforcements 7 unless I provide the structure with an adequate strut resistance to prevent the lateral deflection of girders 1, when wedges 10 are driven,—girders 2 having an equal draw on both of their sides, and in my above referred to Patent #1,716,710 I have claimed, as my therein contained invention in its broad sense, the principle of means to strut the supports against the above referred to draw brought about by reinforcements 7. In my above referred to Patents #1,716,710 and #1,785,214 I have illustrated the strut means contacting the webs of the girders, or beams, with the initially tensioned reinforcements locked to their top flanges, but due to the fact that these reinforcements exercise a onesided draw on the outside girders, or beams, it is apparent that said top flanges, reaching above the strut means, become subjected to shearing strains, and the onesided draw also has a tilting effect on the top parts of the outside girders.

After having dealt with the above I am now coming to that which constitutes my invention herein.

In Figures 1, 3, and 4 I have illustrated my invention to protect flange 3, of girders 1, against the onesided shearing strains, caused by reinforcements 7, by attaching members 11 to the outer side of girders 1. I prefer to seam weld the one end of members 11, preferably, to edge 40 14 of the bottom flange 12, of girder 1, and I attach the other end of members 11, likewise preferably seam welded, to top flange 3 of girder 1, preferably at contact point 15 between flange 3 and web 13, all on the outside of girder 1. Members 11 have a slanting position between points 14 and 15. I place members 11 at suitable intervals.

Due to the position, which I have given members 11, the following is evident:—When the draw from reinforcements 7 asserts its strength on flange 3, that draw will awaken a tensile action in members 11, which is of the same strength as the draw in reinforcements 7, and this tensile action, in members 11, then assumes a strut and

anti-shearing action against the draw which is exercised upon top flange 3 of girder 1 by reinforcements 7.

Whenever I deem it advisable I add bracing material 16, between web 13 and the outside part of flange 12, in order to supply flange 12 with whatever resistance may be required to hold the tensile action in members 11.

The broken lines 6, on Fig. 1, indicate the removable strut as illustrated in my above referred to Patent #1,785,214, and the firm manner in which device 16 braces flange 12 against the indicated strut member 6 will readily be understood, besides which girder 1 becomes materially stiffened thereby. I prefer to seam weld member 16 in its position. Strut 6 is removable after concrete 17 has become hard and concrete 17 then assumes the strut action of 6. These references to bracing material 16, which I have just now made, also hold good with regard to the non-removable strut, which is disclosed in my other above referred to Patent #1,716,710.

As reinforcements 7 exercise an equal draw on both sides of girders 2 it is not necessary to supply girders 2 with members 11.

I have illustrated the most important part of my invention in Fig. 5 in which I have shown other strut members 19, which I attach in a slanting position from the inside edges of flange 3 of girders 1 to girders 2, placing these members 19 one on each side of column 18. Members 19 thereby protect the connections, between girders 1 and column 18, against shearing strains caused by reinforcements 7, these members 19 assuming the required strut and anti-shearing action to protect the said connections (not shown) which hold girders 1 to column 18. These strut members 19 also counteract any inwardly tilting action, which may manifest itself in girders 1 and 2 to which I have made reference in an earlier part of this specification. Whenever I so deem it advisable I place a series of slanting members 19, paralleling each other, between girders 1 and 2.

Girders 2, together with reinforcements 7, reach from either side of the building to its opposite side. The draw, caused by reinforcements 7, has therefore a tendency to clamp girders 2 together, and there can be no lateral movements on girders 2, due to the equal pressure, on both sides of girders 2, by strut members 19.

Girders 2 are always placed in an angular relation to girders 1, and when I position my strut members 19 slantingly between girders 1 and 2 I automatically transplant the strut action of my members 19 to girders 2. Girders 2 reach between the opposed girders 1. The opposed girders 1, that are located in the opposite outside walls of the building, are all furnished with the slanting strut members 19, above described, whereby members 19, through the intermediate inside girders 2, can serve the purpose to clamp the full length of the opposed outside wall girders 1 against each other. Girders 2 are an essential and indispensable part of the steel frame structure, and had I not made my novel and simple invention of placing my members 19 in their slanting position, as above described, I would have had to use added material, between all of the intervening girders 2, to transplant the strut action from outside wall girder 1 to its opposed outside wall girder 1.

I may also attach reinforcements 7 to the bottom flanges of girders 1 and 2 and, in such

case, I attach reinforcements 7 and strut members 19 to the bottom flanges of girders 1 and 2 in the same manner, as above described, in which I attach members 7 and 19 to the top flanges 3 of girders 1 and 2.

Fig. 6 is a plan view of a modification of my invention in which strut supporting means 20, herein shown as a beam, is attached to the inside web 13 of girder 1. The one end of members 19 is attached to the inside edge of top flange 3 of girder 1, in a slanting position, as explained under the description of Fig. 5 above, while the other end of strut members 19 is attached to the strut supporting beams 20. Members 19 are placed on both sides of strut supporting means 20, and then serve the purpose of counteracting the strut and shearing strains on flange 3, of girder 1, caused by reinforcements 7.

The arrows indicate the direction of the draw brought about by reinforcements 7.

Various other modifications may be made without departing from the spirit of my invention.

I claim:—

1. In a series of girders in rectangular formation which form a floor span with reinforcements extending from one girder to the opposite including means to initially tension and lock said reinforcements to the flanges of said girders and members adapted to strut said girders, the combination of said strut members intermediate the adjacent interior sides of said girder rectangular formation.

2. In a series of girders in rectangular formation which form a floor span with reinforcements extending from one girder to the opposite including means to initially tension and lock said reinforcements to the flanges of said girders and members adapted to strut said girders, the combination of said strut members intermediate the adjacent interior flanges of said girder rectangular formation.

3. In the outside girder of a rectangular girder formation which forms a floor span with reinforcements extending from one girder to the opposite including means to initially tension and lock said reinforcements to the flanges of the said girders and members adapted to strut said girders, the combination of said strut members intermediate the inside of said outside girder and those interior sides of said formation which contact said outside girder.

4. In the outside girder of a rectangular girder formation which forms a floor span with reinforcements extending from one girder to the opposite including means to initially tension and lock said reinforcements to the flanges of the said girders and members adapted to strut said girders, the combination of said strut members intermediate the inside of the flange of said outside girder and those interior sides of said formation which contact said outside girder.

5. In a series of girders in rectangular formation which form a floor span with reinforcements extending from one girder to the opposite, said reinforcements in initial tension locked to the top flanges of said girders and strut members intermediate the opposed interior sides of said formation, in combination with tension absorbing material positioned on the outer parts of said girder formation between the lower flange edges and the points of contact between the webs and top flanges.

HENRY SORENSEN.
